UNITED STATES PATENT OFFICE.

PETER V. OLESEN, OF CHICAGO, ILLINOIS.

GAS-BURNING HEATER.

Application filed May 23, 1927. Serial No. 193,431.

This invention has to do with gas burning heaters for use in hot air, hot water, vapor, steam and other similar heating systems.

The principal object of the invention is 5 to provide an improved gas burning heater which is inexpensive to construct, which may be installed in the fire boxes of any of the ordinary heating systems, and which will operate with a very high degree of efficiency.

Other objects and advantages of the invention will be apparent to those skilled in the art upon a full understanding of the construction, arrangement and operation of 15 the improved heater.

One form of the invention is presented herein for the purpose of exemplification, but it will of course be appreciated that the invention is also susceptible of embodiment 20 in other modified forms coming equally within the comprehensive scope of the appended claims.

In the accompanying drawing:

Fig. 1 is a plan view of the improved 25 heater;

Fig. 2 is a vertical section through the heater, taken on the line 2-2 of Fig. 1; and

Fig. 3 is a vertical section through the jet 30 of the heater.

The heater illustrated in the drawing includes a bowl 10, a ring 11, a cover 12, and a jet 13. The bowl 10 is upwardly dished, and is supported on legs 14 within the fire 35 box. The jet 13 is positioned concentrically within the bowl 10, and is in communication with a supply pipe 15 which extends under and is suspended from the bowl by brackets 16. The ring 11 is downwardly 40 dished, and is supported above the bowl in spaced concentric relation to the latter by brackets 17. The cover 12 is also downwardly dished, and is supported above the ring in spaced concentric relation to the latter 45 by brackets 18. The ring is of less diameter than the bowl, and the cover is of still less diameter than the ring.

The jet 13, which is located within the bowl beneath both the ring and the cover, 50 consists of a downwardly opening cylindrical cap 19 and an upwardly opening cylindrical cup 20 having a downwardly extending tubular portion 21. The cap 19 fits snugly over the cylindrical portion of the 55 cup 20. The tubular portion 21 of the cup extends through a central aperture 22 in

the bowl 10, and terminates just above an upwardly directed nozzle 23 in the pipe 15, the top of the nozzle and the adjacent end of the bore in the tubular portion 21 of the cup being tapered as shown to provide ample space for air to enter the jet between the same, and the nozzle being vertically adjustable relative to the pipe by reason of the threaded engagement therewith. 60 The tubular portion 21 of the cup may also be apertured at 24 to permit even more air to enter the jet. The cap 19 is provided adjacent its upper edge with a large number of laterally opening ports 25 and a 70 large number of upwardly opening ports 26, which permit the gas to leave the jet, and the bowl 10 is provided with a few openings 27, which permit still more air to mix with the burning gases between the bowl and the ring and the cover, and also prevent back-firing.

The construction of the jet 13, and the proportioning, spacing and shaping of the bowl, ring and cover, together produce a 80 gas burning unit of great efficiency. The gas entering the heater through the pipe 15 and nozzle 23 is directed laterally and upwardly by the ports 25 and 26 in the jet 13 and ignites within the space enclosed by the bowl, ring and cover, the flames shooting laterally and upwardly through the annular openings between the bowl and the ring and between the ring and the cover, in a large circular mass. The control of 90 the burning gases effected by the parts of the heater assures thorough combustion of the gas and widespread distribution of the heat obtained from the same.

The heater may be easily taken apart for 95 cleaning or shipping, the cover merely resting on the brackets 18 mounted on the ring, and the ring merely resting on the brackets 17 mounted on the bowl. The jet 100 13 may be removed from the bowl by lifting the tubular portion 21 of the cup 20 of the jet up through the aperture 22 in the bowl.

I claim:

1. In a gas burning heater, an upwardly 105 dished bowl, a downwardly dished ring spaced above the bowl, a downwardly dished cover spaced above the ring, and a jet positioned within the chamber formed between the bowl, ring and cover.

2. In a gas burning heater, a large bowl, 110 a smaller ring spaced above the bowl, a

still smaller cover spaced above the ring, and a jet positioned within the upwardly converging chamber formed between the bowl, ring and cover.

5. 3. In a gas burning heater, a bowl, a ring spaced above the bowl, a cover spaced above the ring, and a jet positioned beneath the ring within the chamber formed between the bowl, ring and cover and provided with laterally and upwardly discharging ports.

10. 4. In a gas burning heater, a large upwardly dished bowl provided with air vents, a smaller downwardly dished ring spaced above the bowl, a still smaller downwardly dished cover spaced above the ring, and a jet positioned beneath the ring within the center of the upwardly converging chamber formed between the bowl, ring and cover and provided with laterally and upwardly discharging ports.

15. 5. In a gas burning heater, a bowl, a ring,

seats on the bowl for supporting the ring in spaced upwardly removable association with the bowl, a cover, seats on the ring for supporting the cover in spaced upwardly removable association with the ring, and a jet positioned within the chamber formed between the bowl, ring and cover.

20. 6. In a gas burning heater, a bowl, a ring spaced above the bowl, a cover spaced above the ring, a jet positioned within the bowl and having a downwardly extending tubular portion disposed within an aperture in the bowl, and a supply pipe extending transversely beneath the bowl and having an upwardly opening nozzle beneath and in spaced vertical alignment with the downwardly extending tubular portion of the jet.

25. 35. In testimony whereof I have hereunto subscribed my name.

PETER V. OLESEN.
